1470, 1471, 1472, 1473, 1474, 1475, 1476, 1477, 1478, 1479, 1471, 1480, 1481, 1482, 1483, 1484, 1485, 1486, 1487, 1488, 1489, 1481, 1490, 1491, 1492, 1493, 1494, 1495, 1496, 1497, 1498, 1491, 1500, 1501, 1502, 1503, 1504, 1505, 1506, 1507, 1508, 1509, 1501, 1510, 1511, 1512, 1513, 1514, 1515, 1516, 1517, 1518, 1519, 1511, 1520, 1521, 1522, 1523, 1524, 1525, 1526, 1527, 1528, 1529, 1521, 1530, 1531, 1532, 1533, 1534, 1535, 1536, 1537, 1538, 1539, 1531, 1540, 1541, 1542, 1543, 1544, 1545, 1546, 1547, 1548, 1549, 1541, 1550, 1551, 1552, 1553, 1554, 1555, 1556, 1557, 1558, 1559, 1551, 1560, 1561, 1562, 1563, 1564, 1565, 1566, 1567, 1568, 1569, 1561, 1570, 1571, 1572, 1573, 1574, 1575, 1576, 1577, 1578, 1579, 1571, 1580, 1581, 1582, 1583, 1584, 1585, 1586, 1587, 1588, 1589, 1581, 1590, 1591, 1592, 1593, 1594, 1595, 1596, 1597, 1598, 1591, 1600, 1601, 1602, 1603, 1604, 1605, 1606, 1607, 1608, 1609, 1601, 1610, 1611, 1612, 1613, 1614, 1615, 1616, 1617, 1618, 1619, 1611, 1620, 1621, 1622, 1623, 1624, 1625, 1626, 1627, 1628, 1629, 1621, 1630, 1631, 1632, 1633, 1634, 1635, 1636, 1637, 1638, 1639, 1631, 1640, 1641, 1642, 1643, 1644, 1645, 1646, 1647, 1648, 1649, 1641, 1650, 1651, 1652, 1653, 1654, 1655, 1656, 1657, 1658, 1659, 1651, 1660, 1661, 1662, 1663, 1664, 1665, 1666, 1667, 1668, 1669, 1661, 1670, 1671, 1672, 1673, 1674, 1675, 1676, 1677, 1678, 1679, 1671, 1680, 1681, 1682, 1683, 1684, 1685, 1686, 1687, 1688, 1689, 1681, 1690, 1691, 1692, 1693, 1694, 1695, 1696, 1697, 1698, 1691, 1700, 1701, 1702, 1703, 1704, 1705, 1706, 1707, 1708, 1709, 1701, 1710, 1711, 1712, 1713, 1714, 1715, 1716, 1717, 1718, 1719, 1711, 1720, 1721, 1722, 1723, 1724, 1725, 1726, 1727, 1728, 1729, 1721, 1730, 1731, 1732, 1733, 1734, 1735, 1736, 1737, 1738, 1739, 1731, 1740, 1741, 1742, 1743, 1744, 1745, 1746, 1747, 1748, 1749, 1741, 1750, 1751, 1752, 1753, 1754, 1755, 1756, 1757, 1758, 1759, 1751, 1760, 1761, 1762, 1763, 1764, 1765, 1766, 1767, 1768, 1769, 1761, 1770, 1771, 1772, 1773, 1774, 1775, 1776, 1777, 1778, 1779, 1771, 1780, 1781, 1782, 1783, 1784, 1785, 1786, 1787, 1788, 1789, 1781, 1790, 1791, 1792, 1793, 1794, 1795, 1796, 1797, 1798, 1791, 1800, 1801, 1802, 1803, 1804, 1805, 1806, 1807, 1808, 1809, 1801, 1810, 1811, 1812, 1813, 1814, 1815, 1816, 1817, 1818, 1819, 1811, 1820, 1821, 1822, 1823, 1824, 1825, 1826, 1827, 1828, 1829, 1821, 1830, 1831, 1832, 1833, 1834, 1835, 1836, 1837, 1838, 1839, 1831, 1840, 1841, 1842, 1843, 1844, 1845, 1846, 1847, 1848, 1849, 1841, 1850, 1851, 1852, 1853, 1854, 1855, 1856, 1857, 1858, 1859, 1851, 1860, 1861, 1862, 1863, 1864, 1865, 1866, 1867, 1868, 1869, 1861, 1870, 1871, 1872, 1873, 1874, 1875, 1876, 1877, 1878, 1879, 1871, 1880, 1881, 1882, 1883, 1884, 1885, 1886, 1887, 1888, 1889, 1881, 1890, 1891, 1892, 1893, 1894, 1895, 1896, 1897, 1898, 1891, 1900, 1901, 1902, 1903, 1904, 1905, 1906, 1907, 1908, 1909, 1901, 1910, 1911, 1912, 1913, 1914, 1915, 1916, 1917, 1918, 1919, 1911, 1920, 1921, 1922, 1923, 1924, 1925, 1926, 1927, 1928, 1929, 1921, 1930, 1931, 1932, 1933, 1934, 1935, 1936, 1937, 1938, 1939, 1931, 1940, 1941, 1942, 1943, 1944, 1945, 1946, 1947, 1948, 1949, 1941, 1950, 1951, 1952, 1953, 1954, 1955, 1956, 1957, 1958, 1959, 1951, 1960, 19

to correct curvature several times during the life of the bar.

Inasmuch as the web 1 moves in a tangential path in contact with the rounded wearing face 26 of the suction bar 25, in time the wearing face is flattened, reducing the efficiency of the suction perforations 28 in removing surface water from the web. I have found that the proper curvature of the wearing face 26 for highest efficiency 10 is that obtained by a radius of one and three-sixteenths inches. This curvature is maintained by loosening the clamping bolts 29 and removing the suction bars 25 to a metal planer, the bars being replaced after each planing. This operation 15 can be repeated several times and I find in practice should preferably be done about twice each year. Thus, it is possible to renew the wearing face of the suction bars several times during their life. Any of the well known hardened steels now on the market may be used for 20 the suction bars.

The uprights 15 are connected to an exhausting apparatus or suction pump (not shown) through the suction conduit 30 located at the 25 top of the drying tower 13. Thus, a current of air at high speed is caused to enter the suction perforations 28 in the suction bars during the operation of the device, the perforations being preferably arranged in a double row and in alternating or zigzag relation, one row being disposed at each side of the center or crown of the bar so that when the web 1 passes across the face 26 the suction perforations are not closed, air being thus caused to rush across the surface of the 35 traveling web and into the suction pipes 16, carrying the water with it.

A somewhat similar action takes place in the apparatus of my patent referred to above. In that machine, however, it was necessary to remove the worn suction pipes from the machine and install entirely new ones when the old pipes became worn and inefficient. In the present machine, the suction pipes 16 form a permanent part of the machine, it being necessary only to 40 remove and renew the wearing surfaces of the hardened steel suction bars when the faces of the latter become worn. This is a decided improvement in maintaining the efficiency of the machine and in reducing the cost thereof.

Between the uprights 15, doctors 31 are arranged to remove the surplus water from opposite sides of the upwardly traveling web directly after it leaves the water bath, a group of the suction pipes 16 being disposed directly above each of the doctors, these groups being indicated by numeral 50 32 and consisting of two suction pipes each. Most of the water is removed from the web by these suction pipes, but in order to entirely remove all of the moisture, I cause the web to travel 55 in a zigzag path through guide rollers 33 until the web reaches the top of the drying tower.

Between the rolls 33 and under the traveling web 1, I arrange groups 34 of suction pipes, preferably three in each case, for removing the moisture collected in drops on the under surface of the web by the rolls 33. The rolls 33 act to break up the film of moisture on the wax surfaces of the web into globular form, the segregated moisture being thereupon removed by the 60 suction pipes of the groups 34. The foregoing action is described and claimed in my application, Serial No. 719,243, filed April 6, 1934, for Paper waxing apparatus. Although the web of paper travels at high speed, substantially eleven

hundred feet per minute, the wax web is free of moisture on leaving the drying tower 13.

By adjusting the bolts 23, the ends of the suction pipes 16 may be individually adjusted to bring the wearing face 26 of the suction bar into proper contact with the moving web of paper. This is a very important feature inasmuch as for maximum efficiency the wearing faces of the suction bars must be in proper contact with the web. If desired, the vacuum pipes 16 may be 10 readily removed from the uprights 15 although, as pointed out above, they are intended to form a permanent part of the machine.

For best results, I have found that the clamping bolts 29 should be arranged through the pipes 15 in a slightly upwardly and rearwardly inclined position relative to the web, the axis of each bolt preferably passing through the axis of the pipe and at an angle of 15° with a plane parallel to the web. In this case, the suction pipes are three 20 and one-half inches in outside diameter.

Referring to Fig. 8 of the drawings, in the illustrated modification, the waxing machine comprises a pair of spaced parallel uprights 37 of substantially U shape having hollow 25 walls. Between the uprights are arranged rolls 38 and 39 acting to guide the traveling web 1 upwardly between the front of the uprights. A roller 40 coacts with the roller 39 to guide the paper in a downwardly inclined path to the back 30 of the uprights where rollers 41 and 42 coact to cause the web to travel downwardly in a zigzag path.

Arranged between and at the bottom of the front of the uprights is a tank 43 containing a 35 chilling fluid, preferably water, which is constantly circulated within the tank by means including a pump 44 driven by an electric motor 45. The doctors 46 return the water collected by them to the pump through a pipe 47. Groups 48 40 of suction tubes, opposite sides of the traveling web between the rollers 37 and 38 and between the rollers 39 and 40. Similar groups 49 of suction pipes are disposed between the rollers 40, 41 and 42 under the traveling web. The vacuum 45 groups 48 and 49 are similar to the groups 34 of Figs. 1 to 7, inclusive.

Coacting with the rollers 38 and 42 are positively driven rolls 50 preferably of rubber, which are adapted to be spaced from their coacting rolls 50 by means of a handle 51 having a cam 52 coacting with a stationary plate 53. By manipulating the handles 51, one man may start the web 1 through the machine.

The hollow uprights 37 are connected to a vacuum pump (not shown) by means of a suction conduit 54 at the bottom of the back of the machine. The machine of the modification operates in the same manner as the machine described above in connection with Figs. 1 to 7, inclusive, 60 the web passing through the cold water bath after leaving the wax tank 55 and squeeze rolls 56. The machine of the modification, however, takes little floor space and has a height of only six feet. More suction tubes are used, but the polishing 65 and chilling rolls are entirely eliminated. The efficiency of the machine is increased by recirculating the cold water bath, the web being finally wound on the finished roll 57 at comparatively high speed.

On the uprights and spaced from the outside of the rolls 40 and 41, I arrange a splash guard 58.

From the above description of my invention, it will be apparent to those skilled in the art that I provide a waxing machine which is very effi- 75

cient and effective for the purpose intended. The machine is capable of taking care of webs traveling at very high speed owing to the efficiency of the cooling and drying apparatus. Further, the machine may be operated at high efficiency with slight maintenance expense.

I have illustrated and described my improvements in embodiments which I have found very practical. I have not attempted to illustrate or 10 describe other embodiments or adaptations as it is believed this disclosure will enable those skilled in the art to embody or adapt my improvements as may be desired.

Although I have shown and described certain 15 specific embodiments of my invention, I am fully aware that many modifications thereof are possible. My invention is therefore not to be restricted except in so far as is necessitated by the prior art and by the spirit of the appended claims.

20 Having thus described my invention, what I claim as new and desire to secure by Letters Patent is:

1. In a waxing machine, the combination with a stainless steel suction pipe having a longitudinal slot intermediate the ends thereof, and a hardened steel suction bar having a transversely rounded wearing face and a base fitting within said slot, the bar being provided with suction perforations, of a series of clamping bolts arranged through said pipe at substantially right angles to said slot for releasably clamping the base of said bar in place, said bar being relatively deep between said base and said face to provide for machining the face to correct curvature several times during the life thereof.

2. In a waxing machine, the combination with a suction pipe having a longitudinal slot intermediate the ends thereof, and a suction bar having a transversely rounded wearing face and a base fitting within said slot, the bar being provided with suction perforations, of a series of clamping bolts arranged through said pipe for releasably clamping the base of said bar in place between the sides of said slot, said bar being relatively deep between said base and said face to provide for machining the face to correct curvature several times during the life thereof.

3. In a waxing machine, the combination with a stainless steel suction pipe having a longitudinal slot intermediate the ends thereof, and a hardened steel suction bar having a rounded wearing face and a base fitting within said slot, the bar being provided with perforations, of means compressing said pipe for releasably clamping the base of said bar in place between the sides of said slot, said bar being relatively deep between said base and said face to provide for machining the face to correct curvature several times during the life thereof.

4. In a waxing machine, the combination with a suction pipe having a longitudinal slot intermediate the ends thereof, and a suction bar having a rounded wearing face and a base fitting within said slot, the bar being provided with perforations, of means compressing said pipe for clamping the base of said bar in place between the sides of said slot.

5. In a waxing machine, the combination of a suction pipe having a longitudinal slot inter-

mediate the ends thereof, and a suction bar having a rounded wearing face and a base removably fitting said slot, the bar being provided with suction perforations, said bar being relatively deep between said base and said face to provide for machining the face to correct curvature several times during the life thereof.

6. In a waxing machine, the combination with spaced hollow uprights, and a suction pipe disposed therebetween, the inner walls of the uprights having openings at the ends of the pipe, of end plates adjustably mounted on the inner walls of the uprights and having inwardly projecting forked lugs, cylindrical end members telescoped within the ends of said pipe and having lateral bosses facing said lugs, and bolts journaled to said lugs and threaded to said end members in said bosses for adjusting the ends of said pipe transversely of said uprights.

7. In a waxing machine, the combination with spaced hollow uprights, and a suction pipe disposed therebetween, the inner walls of the uprights having openings at the ends of the pipe, of end plates mounted on the inner walls of the uprights, cylindrical end members in telescoped relation with the ends of said pipe, and means for adjusting said end members relative to said end plates.

8. In a machine of the class described, the combination with spaced uprights constituting suction headers, of opposed suction pipe mounting plates on the inner sides thereof having horizontal undercut seats and slotted lugs, suction pipes provided with perforated faces, coupling members telescoped with said suction pipes and having flanges engaging said seats on said mounting plates, and adjusting screws rotatably engaging said slotted lugs on said mounting plates and having threaded engagement with said coupling members whereby the suction pipes are adjustably supported.

9. In a machine of the class described, the combination with spaced uprights constituting suction headers and provided with opposed suction pipe seats on their sides, of suction pipes provided with perforated faces, coupling members telescoped with said suction pipes and slidably supported in said seats, and adjusting means for said coupling members in said seats whereby the suction pipes are adjustably supported.

10. In a device of the type described, the combination with suction pipes provided with perforated faces, of spaced members constituting suction headers and provided with opposed suction pipe seats transverse of the pipes, means operatively associated with said pipes and cooperative with said seats to adjustably support the pipes thereagainst, and means for adjusting the pipes transversely, of said seats.

11. In a device of the type described, the combination with suction pipes provided with perforated faces, of spaced members constituting suction headers and provided with opposed suction pipe seats transverse of the pipes, means operatively associated with said pipes and cooperative with said seats to adjustably support the pipes thereagainst, and means for adjusting the pipes in said seats.

RALPH A. HAYWARD.
